Inventor:
Carl M. Dreher,

Atty.

UNITED STATES PATENT OFFICE

CARL M. DREHER, OF NORA SPRINGS, IOWA

SCOOP

Application filed July 6, 1928. Serial No. 290,784.

My said invention relates to a scoop of the type used by grocers for handling sugar, coffee and other groceries and also useful for many other purposes. It is an object of my 5 invention to provide a device of this character which shall be highly sanitary in use, in order to make it possible to handle bulk groceries or analogous material in accordance with the best sanitary practice.

10 Another object of the invention is to provide a device of this character which shall be practically free from any tendency to spill the material contained therein, under any ordinary conditions of use.

15 A further object of the invention is to provide a device of this character in which the greater capacity of the device shall be at the rear of the scoop instead of at the front.

Referring to the drawing, which is made a 20 part of this application and in which similar reference characters indicate similar parts:

Fig. 1 is a side elevation of my device, and
Fig. 2, a plan of the same.

Fig. 3 is a vertical sectional view of the 25 scoop.

In the drawing reference character 10 indicates the flat bottom of the scoop at the rear end of the same, said bottom having a flat face 11 tapering upward from the face 10 toward the front of the scoop. The side walls 12 flare from the bottom of the scoop toward the upper margin and the rear end of the scoop is rearwardly bulged, so that the hollow space extends back furthest at about the mid-point 30 in the height of the scoop. The bottom, comprising the parts 10 and 11, tapers from the rear of the scoop toward the front and the sides follow the contour of the bottom so that the scoop is narrower at the front than further back.

Several purposes are served by the construction just described. The flat bottom 10 provides convenient means for supporting the scoop on a flat surface either when it is 40 empty or when it is filled. The inclined face 11 tends to throw the material back toward the rear of the scoop so that the scoop will stand steady and so that it can be more easily handled. The curved sides increase the capacity of the scoop, particularly toward the

rear of the same, thus throwing the weight toward the point of support. The fact that the forward part of this scoop is narrower than the rear helps to prevent accidental spilling in tilting this scoop as the material tends 55 to jam somewhat at the front of the scoop though not sufficiently to interfere with dumping of the same when it is sufficiently tilted. The fact that the forward portion of the bottom is elevated helps to prevent spilling of the material in the scoop, which is thrown back toward the rear instead of leaking out at the front. The fact that the scoop is smaller at the front makes the scoop more 60 convenient to be inserted into a bag into which it is to be dumped, whereas the scoops commonly in use have a flat bottom fully as wide at the front end as at the rear, or else are cylindrical so that they will not stand up but will roll over and spill.

The rear end 12 of the scoop extends upward to a considerable height above the hand-grip 13. The purpose of this is to afford the user a bearing for his thumb and also to prevent him from reaching over the top of the 70 scoop with his thumb. It will be understood that the last-named practice, which is common with scoops of ordinary types, is unsanitary as the user may have on his hands particles of other groceries or kerosene or other 75 matter that will give an undesirable appearance or flavor to the groceries being parcelled out. For further assistance to the dealer in handling the scoop the handle 13 is widened in a vertical sense at the rear end and is bent 80 downward to a certain extent. This tends to 85 throw the hand downward from the rear wall 12 at the top. The handle furthermore is narrower in a horizontal sense than it is in a vertical sense; i. e., it is substantially elliptical 90 or oblong and thus can be held firmly in the hand to prevent accidental tilting of the scoop and spilling of material, as very frequently happens with the ordinary scoops having round handles.

It will be obvious to those skilled in the art 95 that various modifications may be made in my device without departing from the spirit of the invention and therefore I do not limit myself to what is shown in the drawing and 100

described in the specification but only as indicated in the appended claim.

Having thus fully described my said invention, what I claim as new and desire to secure by Letters Patent, is:

5 A scoop closed at the rear end, bottom and sides, the rear end being convex and having a forwardly-extending guard at the top, and a downwardly-inclined handle elliptical in cross-section at said rear end approximately 10 midway of its height whereby to prevent the thumb of the user from engaging the contents of the scoop.

In testimony whereof I affix my signature.

CARL M. DREHER.
